CLAIM

The ornamental design for a cosmetic casing, as shown and described.

DESCRIPTION

FIG. 1 is a perspective view of a cosmetic casing showing my new design, in which the inner structures shown in broken lines are for illustrative purposes only and form no part of the claimed design;

FIG. 2 is a front elevational view thereof;

FIG. 3 is a rear elevational view thereof, in which the hinge area shown in broken lines is for illustrative purposes only and forms no part of the claimed design;

FIG. 4 is a top plan view thereof;

FIG. 5 is a bottom plan view thereof, in which the hinge area shown in broken lines is for illustrative purposes only and forms no part of the claimed design;

FIG. 6 is a left side elevational view thereof; and,

FIG. 7 is a right side elevational view thereof.
